UNITED STATES PATENT OFFICE.

JEROME G. CLINE, OF PLAINFIELD, NEW JERSEY.

DESIGN FOR AN INSULATOR-BODY.

49,204.

Specification for Design.

Patented June 20, 1916.

Application filed April 1, 1916. Serial No. 88,400. Term of patent 14 years.

To all whom it may concern:

Be it known that I, JEROME G. CLINE, a citizen of the United States of America, residing at Plainfield, in the county of Union and State of New Jersey, have invented a new, original, and ornamental Design for Insulator-Bodies, of which the following is a specification, reference being had to the accompanying drawing, forming a part thereof.

In the drawing Figure 1 is a top view in

perspective; and Fig. 2 is a bottom view in perspective of an insulator body of my new an improved design.

I claim:—

The ornamental design for an insulator body as shown.

JEROME G. CLINE.
